(57) **CLAIM**

The ornamental design for a mobile electronic device, as shown and described.

DESCRIPTION

FIG. 1 is a front perspective view of a mobile electronic device according to a first embodiment of our new design; FIG. 2 is a rear perspective view thereof;

FIG. 3 is a front plan view thereof;

FIG. 4 is a back plan view thereof;

FIG. 5 is a right side view thereof;

FIG. 6 is a left side view thereof;

FIG. 7 is a top plan view thereof;

FIG. 8 is a bottom plan view thereof;

FIG. 9 is a front perspective view of a mobile electronic device according to a second embodiment of our new design;

FIG. 10 is a rear perspective view thereof;

FIG. 11 is a front plan view thereof;

FIG. 12 is a back plan view thereof;

FIG. 13 is a right side view thereof;

FIG. 14 is a left side view thereof;

FIG. 15 is a top plan view thereof;

FIG. 16 is a bottom plan view thereof;

FIG. 17 is a front perspective view of a mobile electronic device according to a third embodiment of our new design;

FIG. 18 is a rear perspective view thereof;

FIG. 19 is a front plan view thereof;

FIG. 20 is a back plan view thereof;

FIG. 21 is a right side view thereof;

FIG. 22 is a left side view thereof;

FIG. 23 is a top plan view thereof;

FIG. 24 is a bottom plan view thereof;

FIG. 25 is a front perspective view of a mobile electronic device according to a fourth embodiment of our new design;

FIG. 26 is a rear perspective view thereof;

FIG. 27 is a front plan view thereof;

FIG. 28 is a back plan view thereof;

FIG. 29 is a right side view thereof;

FIG. 30 is a left side view thereof;

FIG. 31 is a top plan view thereof; and,

FIG. 32 is a bottom plan view thereof.

The broken lines represent portions of the mobile electronic device that form no part of the claimed design.

1 Claim, 24 Drawing Sheets
